UNITED STATES PATENT OFFICE.

CHRISTOPHER E. HERTLEIN, OF NEW YORK, N. Y.

DESIGN FOR GIMP.

SPECIFICATION forming part of Design No. 22,351, dated April 18, 1893.

Application filed February 28, 1893. Serial No. 464,116. Term of patent 3½ years.

To all whom it may concern:

Be it known that I, CHRISTOPHER E. HERTLEIN, a citizen of the United States, residing in the city of New York, county and State of New York, have invented and produced a new and original Design for Gimp, of which the following is a specification, reference being had to the accompanying drawing, in which the figure is a view of a piece of gimp showing my design.

The leading features of the design for gimp consist of a series of narrow or stem-like portions, alternating with enlarged portions, which are connected to a border on one side

by cords or threads. The stem-like portions 15 1, and enlarged portions 2, have the appearance of having cord wound around them. The border or braid 3 is connected by cords 4, 5, between the enlarged portion and said border, as shown. 20

What I claim is—

The design for gimp, substantially as herein shown and described.

CHRISTOPHER E. HERTLEIN.
